United States Patent Office.

JOHN B. HOFFMAN, OF PHILADELPHIA, PENNSYLVANIA.

Letters Patent No. 71,757, dated December 3, 1867.

IMPROVEMENT IN DRY GAS-REGULATORS.

The Schedule referred to in these Letters Patent and making part of the same.

TO ALL WHOM IT MAY CONCERN:

Be it known that I, JOHN B. HOFFMAN, of Philadelphia, Pennsylvania, have invented an Improvement in Gas-Regulators; and I do hereby declare the following to be a full, clear, and exact description of the same.

My invention consists of a bellows-like receiver applied to a gas-regulator, substantially as described hereafter, so as to obviate the necessity of using the fluids which have been heretofore employed, and which have a tendency to corrode the metal parts of a regulator.

The invention further consists of a certain chamber, with a tight detachable cap arranged on the top of the regulator, in the manner and for the purpose described hereafter.

In order to enable others skilled in the art to make and apply my invention, I will now proceed to describe its construction and operation, reference being had to the accompanying drawing, which forms a part of this specification, and in which—

Figures 1 and 2 are vertical sections of my improved gas-regulator, with the receiver and valve in different positions, and

Figure 3 a plan view.

Similar letters refer to similar parts throughout the several views.

A is the outer casing of the regulator, near the lower end of which is a horizontal partition, d, the space between the latter and the bottom plate B being divided by a vertical partition, a, into two compartments, C D, the former communicating with an outlet or distributing-pipe, E, and the latter with an inlet-pipe, F. At or about the centre of the casing A, and secured to the partition d, is a cylinder, G, which communicates through an opening, b, with the compartment D, and at the top of this cylinder is a screw-cap, e, having an opening, y, through which passes a conical valve, f, suspended from the top e of a receiver, H. The body of this receiver is of leather, or other flexible material, impervious to gas, is secured at its lower edge to the partition d, and is corrugated, as shown in the drawing, so that it may be extended and contracted vertically, in the same manner as bellows of a similar form. The receiver communicates through an opening, b', with the chamber C, and from the top of the receiver projects a rod, i, through the top of the casing A, and into a chamber, I, on the top of the said casing, the chamber being covered by a perfectly tight but detachable cover or cap, j, and on a disk, k, secured to the rod i, within the chamber, rest one or more weights, x. Near the bottom of the casing A are two tubes, n n, one communicating with the compartment C, and the other with the compartment D, and each tube has a screw-cap at its outer end. The pipe F communicates with the street-main, and conducts the gas from the latter to the compartment D, from which it passes through the tube G to the receiver H, and thence through the opening b' and compartment C to the distributing-pipe E.

Such a weight is placed upon the disk k that when the pressure within the receiver is in excess of the amount required, the receiver will be extended, and the valve f will be raised until the opening y is so contracted, and the flow of gas is so retarded, that the pressure within the receiver will be reduced to the extent required. In like manner, a decrease of the pressure within the receiver will be followed by a contraction of the latter, the descent of the valve, and such an enlargement of the opening y as will permit the gas to pass into the receiver as rapidly as is necessary to restore the pressure in the latter. By increasing or reducing the weight upon the disk k, any desired pressure may be maintained within the outlet or distributing-pipes, this alteration of the weights and regulation of the pressure being effected without interfering with the continuous flow of gas through the regulator.

Any matter which condenses within the regulator, or within the pipes E F, will flow into the compartments C D, the interruption of the flow of gas in consequence of the stoppage of the passages being thus prevented. The condensed material may be withdrawn from the compartments C D at any time, by removing the caps on the tubes n n.

By the use of a bellows-like receiver, as above described, the corrosion of parts of the regulator which occurs when fluids are employed is prevented, the apparatus is cheaper and more uniform in its action than those in which fluids are used, and is not affected by ordinary changes in temperature.

Should the receiver be injured, no escape of gas from the regulator can take place, excepting where the rod i passes through the top of the casing; and even should there be a slight leakage here, the tight cap j of the

chamber I prevents the gas from escaping beyond the latter, while access to the weights x is readily obtained by the removal of the cap.

I claim as my invention, and desire to secure by Letters Patent—

1. A bellows-like receiver, H, applied to a gas-regulator, and connected to the valve of the latter substantially as described, so that as the pressure of the gas varies, the receiver will expand or contract, and the opening for the passage of the gas will be increased or diminished in size.

2. The chamber I, and its tight detachable cap j , arranged on the top of the regulator in respect to the weights x , as and for the purpose set forth.

In testimony whereof, I have signed my name to this specification in the presence of two subscribing witnesses.

J. B. HOFFMAN.
